[57] CLAIM

The ornamental design for a stand for an air conditioning coil, as shown and described.

DESCRIPTION

FIG. 1 is a perspective view of a stand for an air conditioning coil showing our new design;

FIG. 2 is a side elevational view, the opposite side being a mirror image thereof;

FIG. 3 is an end elevational view, the opposite end being a mirror image thereof;

FIG. 4 is a top plan view thereof; and,

FIG. 5 is a bottom plan view thereof.

The broken line showings of a second stand and air conditioning coil in FIG. 1 are for illustrative purposes only.

FIG. 1

FIG. 4

FIG. 3

FIG. 2

FIG. 5
